UNITED STATES PATENT OFFICE.

WILLIAM LESLIE GUY, OF BIRMINGHAM, ENGLAND, ASSIGNOR TO AMAC LIMITED, OF BIRMINGHAM, ENGLAND, A BRITISH COMPANY.

CARBURETOR.

Application filed December 9, 1924, Serial No. 754,825, and in Great Britain December 15, 1923.

This invention relates to carburetors of the kind embodying a plug throttle valve sliding across the air passage and two (or more) jet nozzles of which one is an idling 5 or slow-running nozzle, the plug valve being generally bevelled upwards on the air inlet side, on which side the main jet of the two is placed.

With this kind of carburetor there is generally either too rich or too weak a mixture 10 at some point or points in the throttle curve, causing what are known as "flat spots". It is the object of the present invention to provide a construction of carburetor of 15 this kind in which this defect is minimized or eliminated.

According to this invention, the inlet of the tube of the idling nozzle is connected by a passage with the outlet of the tube of 20 the next nozzle to come into operation.

The result is that at slow speeds air alone passes along the passage to the tube of the slow-running nozzle, but, as the throttle is opened and the draught of air over and 25 through the slow-running tube increases, the air travelling along the passage takes up some fuel from the main jet nozzle which compensates for the tendency to become over-weak.

29 Preferably the passage is vented to the main air passage, this vent forming the normal outlet from the main jet tube, and with this vent may co-operate a sealing valve to enable a rich mixture to be obtained at starting. The sealing valve may also function 35 to control the quality of the mixture.

In the accompanying drawings,

Figure 1 is a vertical section showing one 40 form of carburetor embodying this invention, with the throttle in position for starting and slow running.

Figure 2 is a similar view partly in elevation showing the throttle slightly raised.

45 Figures 3 and 4 are partial vertical sections showing the throttle and air control valves in other positions.

Figure 5 is a transverse section on the line 5—5 of Figure 3, and

50 Figure 6 is a fragmentary sectional plan of Figure 5.

Like letters indicate like parts throughout the drawings.

In this construction, there is a horizontal 55 air passage A with a vertical tubular branch B in which slides a plug throttle valve C

which controls the travel of air along the horizontal passage. The bottom end of this plug valve is closed and is bevelled upwards at C² towards the air intake A².

In the lower wall of the air passage is an 60 aperture which is filled by means of a block D which carries the jet nozzles and tubes.

The float chamber E is preferably fitted beneath the air passage and a screw E² screwing into the block D may serve to hold 65 the cup of the float chamber in place against a circular flange E³ carried by the body of the air passage.

The air passage is preferably circular in 70 cross section, but the block D is flat at the top, and this flat top lies slightly below the bottom of the air passage A, so that there is a flat surfaced recess A³ in the bottom of the air passage just beneath the plug valve C (see Figure 5). The lower end C³ of the 75 plug valve C is adapted to enter this recess.

On the side of the block D adjacent to the outlet end of the main air passage is a short vertical recess D² through which passes a small jet nozzle or other suitable fuel or 80 fuel emulsion supplying device. This is preferably a nozzle F dipping into the float chamber at F². The recess D² forms the slow-running tube, and, at a suitable level therein, which may be the bottom of it or 85 thereabout, leads off a small horizontal passage D³ leading firstly to a well D⁴ at or near the centre of the block, the well being in effect a vent to the small passage D³ leading 90 into the main air passage.

From this well the passage D³ enlarges 95 at D⁵ and leads off to the side of the block where it is open to the atmosphere. This part D⁵ of the passage forms a tube for the main jet G (dipping into the float chamber at G²), the tip of which enters the enlarged passage D⁵ instead of, as usual, the main air passage, and its chief communication with the main air passage is through the vent 100 formed by the well D⁴.

Assuming the plug throttle valve C to be in its lowest position, the recess A³ (Figure 5) just above the block D is cut off altogether and no fuel can be drawn out of either jet nozzle. If the plug valve is raised 105 slightly, as shown in Figure 1, the recesses A³ will be shallow. Air is drawn up this recess and also over the top of it. By selecting suitable proportions the right slow-running mixture can be easily obtained. 110

It will be readily understood that as the plug throttle valve is raised this recess A³ increases in cross-sectional area very rapidly, more rapidly than does the area of the passage above the block and in the plane X X of the nozzle F. Thus, when the throttle valve is only a little way open a state is reached when the cross-sectional area of the passage over the block (as obtained in the plane of the nozzle F at X X Figure 6) is equal to the cross-sectional area of the throttle opening, and this position is hereinafter called the "equal area" position of the throttle valve. Figure 3 illustrates this.

As the throttle valve is opened up towards this equal area position the delivery from the idling nozzle F increases, but preferably just before the equal area position is reached the capacity of this nozzle is reached. Thus from this point up to the equal area position the mixture would tend to weaken, but this is counteracted by the increasing amount of air which passes along the passage D² from the main jet nozzle tube D⁵ to the idling nozzle tube D², taking with it a certain amount of fuel from the main nozzle. The air passing the main jet nozzle is then travelling only slowly, but it is sufficient to pick up some fuel from the main jet nozzle and carry it into the well and along the small passage D³ to the idling tube.

As the throttle is raised beyond the equal area position and in the position as shown by Figure 3, suction becomes more and more keen over the mouth of the well D⁴ and gradually, as the throttle is raised, the suction over the idling nozzle F has less effect on the latter and becomes effective over the well D⁴. Thus fuel is drawn out of the main jet nozzle as well as a small amount from the idling nozzle.

It is owing to the interconnection of the idling and main tubes that the tendency to weakness of the mixture is prevented as the suction is being transferred from the idling jet to the main jet.

If desired, there may be a sliding valve H passing through the plug throttle valve C and adapted to close, or partially close, the mouth of the well D⁴. This valve may take the form of a piece of rod of suitable dimensions controlled independently of the plug throttle valve. Its lower edge H² is adapted either to seat in the mouth of the well or round the well as shown, so that, when starting up, suction along the idling nozzle

tube does not draw any uncarbureted air down the well, and therefore the mixture can then be slightly richer than usual. Varying the vertical position of this valve H also varies the velocity of the air over the mouth of the well so that the valve functions also to control the mixture during normal running when the suction is on the main jet nozzle only. Figure 4 illustrates the use of the valve H when the throttle C is half open, and the arrows in this and the other views show the variations in the direction of flow at the several throttle positions.

Alternatively the foot of the valve does not completely seal the mouth of the well, and to prevent this the foot of the valve is nicked or roughened, as, for example, by forming two or more diametrical cross cuts H³ (Figure 4) in it, so that there is always a slight leak of air downwards into the well even though this mixture valve is shut.

By this means one of the great defects of carburetors of this type is overcome, and it is impossible to detect any sluggishness of the engine due to overrichness of the mixture or over weakness as the throttle is opened up slowly or closed slowly. This means that the well known "flat spots" are largely eliminated.

What I claim as my invention and desire to secure by Letters Patent of the United States is:—

1. A carburetor of the type described including an idling nozzle and a main nozzle adapted to come into operation successively, a tube for each nozzle, and a passage connecting the inlet of the tube of the idling nozzle with the outlet of the tube of the said main nozzle, a main air passage in the carburetor and a vent therefor in the passage connecting the said tubes.

2. A carburetor of the type described including an idling nozzle and a main nozzle adapted to come into operation successively and a tube for each nozzle and a passage connecting the inlet of the tube of the idling nozzle with the outlet of the tube of the said main nozzle, and a main air passage in the carburetor and a vent therefor in the passage connecting the said tubes and a sealing valve to control the outlet of said vent.

3. The device of claim 2 said valve having an edge provided with leakage passages.

In testimony whereof I have signed my name to this specification.

WILLIAM LESLIE GUY.
